EARTH HANDLING IMPLEMENT

Laurence L. Reckler, Sparks, Nev.

Application July 4, 1944, Serial No. 543,466

25 Claims. (C.I. 262—2)

1

This invention relates in general to an improved earth handling implement, and in particular the invention is directed to, and it is an object to provide, an earth transporting implement embodying a rotary bowl unit, together with drive and control mechanisms therefor, of novel construction and operation.

Another object of the present invention is to provide an earth transporting implement embodying a rotary bowl unit which includes a loading opening with which a movable door assembly cooperates, and a power unit operatively connected with the bowl by a driving mechanism to rotate said bowl in either direction, selectively; the door assembly being opened or closed by said power unit in advance of rotative movement of the bowl thereby.

A further object of this invention is to provide an earth transporting implement, as in the preceding paragraph, in which such driving mechanism is arranged so that actuation thereof in one direction and when the door assembly is open, first closes the door assembly and then rotates the bowl; and so that actuation of said mechanism in the opposite direction and when the door assembly is closed, first acts to open said door assembly followed by rotation of the bowl if so desired.

It is also an object of this invention to provide an earth transporting implement including a rotary bowl unit having a loading opening and a movable door assembly cooperating therewith; a portion of the door assembly carrying an earth cutting and digging blade, and said portion being operative, when the assembly is open and the bowl disposed in a predetermined position, to dig and load earth into the bowl. The rotary bowl unit also is arranged so that the door assembly may be opened with the loading opening uppermost for loading of the bowl by a power shovel, drag line, or chute. Thus, the rotary bowl unit is self-loading, or may be loaded by a separate implement.

An additional object of this invention is to provide an earth transporting implement having a rotary bowl unit which is foraminous in part, whereby the bowl when loaded and rotated can be employed for screening, sifting, separating, mixing or washing, together with distribution of, the material therein; there being means employed to prevent loss of material through the foraminous portion of the bowl during loading and transporting thereof. The implement is especially useful in surface mining, road construction, or

2

the like, wherein operations, as above, are necessary.

These objects I accomplish by means of such structure and relative arrangement of parts, as will fully appear by a perusal of the following specification and claims.

In the drawings similar characters of reference indicate corresponding parts in the several views:

Figure 1 is a side elevation of the implement 10 with the rotary bowl unit shown with the door assembly open and in digging position.

Figure 2 is an enlarged fragmentary plan view illustrating the rotary bowl unit and adjacent parts.

Figure 3 is a sectional elevation on line 3—3 of Fig. 2, showing the rotary bowl unit with the door assembly open and in digging position.

Figure 4 is a sectional elevation similar to Fig. 3, but showing the door assembly moved part way toward closed position.

Figure 5 is likewise similar to Figs. 3 and 4, but shows the door assembly fully closed and the bowl shifted upwardly to carrying or rotative position.

Figure 6 is an enlarged sectional elevation 25 showing the bowl with the door assembly open, and in position for loading of said bowl by a separate implement.

Referring now more particularly to the characters of reference on the drawings, the implement comprises a main frame, indicated generally at 1, which includes transversely spaced longitudinally extending side plates 2 rigidly connected together by suitable cross members; the main frame 1 being supported adjacent its rear end by transversely spaced ground engaging wheels 3. At the forward end the main frame 1 is supported by a swivel truck 4, which includes wheels 5 and a forwardly extending draft tongue 6 adapted for connection with a tractor.

40 A rotary bowl, indicated generally at 7, is disposed between the side plates 2 intermediate the rear wheels 3 and front truck 4; said rotary bowl being disposed with its axis extending horizontally and transversely of the present implement.

45 The rotary bowl 7 includes substantially circular end walls 8 which are turnably mounted on and supported by a non-rotatable, tubular cross shaft 9 whose outer ends are carried in slide blocks 10 which ride in guided relation in up-50 standing arcuate slots 11 in corresponding side plates 2; the slots 11 being formed concentric to another cross shaft 12 which extends between the side plates 2 to the rear of the rotary bowl and for the purpose as will hereinafter appear.

55 The cross shaft 9 is supported adjacent oppo-

site ends, and for vertical adjustment of the bowl, by means of corresponding bellcranks 13 which are pivotally mounted intermediate their ends to corresponding side plates 2, as at 14; said bellcranks being disposed between the ends of the rotary bowl 7 and said plates 2, with one leg 15 of each bellcrank projecting forwardly from the corresponding pivot 14, and the other leg 16 extending upwardly from said pivot. At the forward ends thereof the legs 15 are longitudinally slotted, as at 17, and adjacent portions of the cross shaft 9 project through and ride in such slots. These slotted portions of the legs 15 form in effect lost-motion connections. At their upper ends the legs 16 are connected by a rigid cross beam 18, and a cable-type block and tackle unit 19 connects between said cross beam 18 centrally of its ends and a corresponding but rearward point on the main frame 1, as clearly shown in Fig. 1. The block and tackle unit 19 includes a pull reach 20 which extends forwardly along one side of the main frame 1 about suitable direction-changing sheaves 21, and said pull reach is adapted at its forward end to connect with the power winch (not shown) on the tractor. As is evident, actuation of the pull reach 20 in a direction to shorten or lengthen the block and tackle unit 19 will result in swinging of the bellcranks 13 in a direction to raise or lower the bowl, respectively.

The rotary bowl is formed on one side with a transverse loading opening 22 of substantial circumferential extent, but of an extent somewhat less than 180°. On the side generally opposite the opening 22, and for a circumferential extent of approximately 180° the side wall of the bowl is perforate or foraminous from end to end thereof, as shown at 23.

The load opening 22 is adapted to be closed by a door assembly which comprises the following:

An arcuate door 24 matchingly engages the outside of the bowl unit on one side of the opening 22 and extends from end to end of the latter; said arcuate door being adapted for circumferential sliding movement from a position clear of opening 22, as shown in Fig. 3, to a position closing substantially one-half of said opening, as shown in Fig. 5. This arcuate door is supported from the ends and for such sliding movement by radial legs 25 of bellcranks 26, one of which is disposed at each end of the bowl; such bellcranks each including another leg 27 disposed at substantially a right angle to leg 25. The bellcranks 26 are rotatably journaled intermediate their ends on shaft 9, and inwardly of the bowl lifting legs 15.

The remaining one-half of opening 22 is adapted to be closed by another door 28 which is substantially straight both transversely and circumferentially of the bowl unit; said door 28 being pivoted along one side to the bowl unit, on a transverse pivot 29, whereby the door 28 can swing from a closed position relative to opening 22, as shown in Fig. 5, to an open and outwardly projecting position substantially tangentially of the bowl, as shown in Fig. 3.

At the side opposite the pivots 29 the door 28 is formed with a transversely extending ground cutting and digging blade 30; said blade substantially contacting the arcuate door 24 when doors 24 and 28 are closed. (See Fig. 5.) The door 28 includes rigid generally radially inwardly extending side wings 31 which serve to guide material into the bowl when the door 28 is open and in ground digging position.

The assembly of doors 24 and 28 is opened or closed, and the bowl unit 7 is rotated, by a power drive and control mechanism which comprises, at each end of the bowl unit, the following:

5 A relatively large-diameter sprocket 32 is rotatably mounted on the tubular cross shaft 9, but held thereon against axial displacement; said sprocket being disposed axially outwardly of the corresponding bellcrank 26. The bellcrank 26 and corresponding side wing 31 are disposed in the same radial plane. An elbow link 33 connects at one end with the sprocket 32 at an eccentric point 34, and connects at the other end, as at 35, to said corresponding side wing 31 radially inwardly from the door 28 and adjacent the edge opposite door pivot 29; the elbow of link 33 extending or bowing in a direction away from cross shaft 9, and opposite bellcrank 26.

When the door assembly is closed, as shown in Fig. 5, the elbow link 33 is disposed with the elbow closely adjacent cross shaft 9, whereby the pivot points 34 and 35 pass beyond dead center relative to the axis of said shaft, which tends to maintain door 28 closed.

20 The bellcrank leg 27 is formed at its outer end with a rounded cam face 36 which is adapted to be engaged by an adjacent edge portion of the corresponding side wing 31, and a flexible link 37, such as a short length of cable, connects between the bellcrank leg 27 and said side wing 31 adjacent and in generally intersecting relation to said cam face. The link 37 connects to side wing 31 adjacent its inner side and at the end opposite pivot 29.

25 A stop 38 on the adjacent end wall 8 of the rotary bowl unit at a point approximately opposite the door 28 is adapted to be engaged by a corresponding stop 39 on the sprocket 32, whereby to limit rotative movement of said sprocket relative to the bowl in the direction shown by the arrow in Fig. 3.

The sprockets 32 are arranged to be simultaneously driven, and in either direction selectively, by the following arrangement:

30 45 Endless chains 40 connect between said sprockets and relatively smaller drive sprockets 41 on cross shaft 12; said chains remaining under proper driving tension regardless of the vertical adjustment of the bowl 7, for the reason that the path of movement of the cross shaft 9 is concentric to the axis of cross shaft 12. The cross shaft 12 is driven through the medium of a power transmission unit, indicated generally at 42, from an engine 43 supported by the frame 1 at its rear end, and which engine and power transmission unit may be suitably housed. The power transmission unit 42 includes a change-speed transmission 44 and a reversing gear unit 45, each of which is provided with a suitable control lever which may be actuated from the tractor by remote control means (not shown).

35 60 When the rotary bowl unit is in lowered position adjacent the ground for digging and loading, its rotative movement in a clockwise direction is limited by means of dogs 46 on the bowl which strike upwardly unyielding cooperating stops 47 from below, said stops 47 being pivotally mounted on a cross member 48 of the main frame for spring-returned downward yielding movement upon engagement of the stops 46 therewith from above, so as not to limit counter-clockwise rotation of the bowl when the same is in lowered position.

65 70 In operation, and to open the door assembly from the closed position shown in Fig. 5 to the

open and digging position shown in Fig. 3, the rotary bowl unit is first lowered to adjacent the ground line and to such position that the stops 46 engage the stops 47 from beneath the latter so as to limit clockwise movement of the bowl. The sprockets 32 are then driven in the direction shown by the arrow in Fig. 3, which causes the elbow link 33 to swing radially away from the cross shaft 9 and to force the door 28 to its open or tangential position. When door 28 is fully open, elbow links 33 abut against stops 49 on side wings 34, and cooperating stops 38 and 39 on the bowl and sprockets are likewise engaged. As the door 28 moves to such open position the flexible link 37 pulls on the bellcrank 26 and causes it to swing about shaft 9 in a direction which opens the sliding door 24.

With the assembly of doors 24 and 28 thus opened, as shown in Fig. 3, and with the rotary bowl unit lowered so that stops 46 engage stops 47 from beneath, the implement is ready for a digging and loading operation. With advance of the implement, the blade 30 digs below the ground surface and the loosened material flows over the open door 28, which then is serving as a loading apron, and passes into the rotary bowl unit.

When the bowl 1 is in loading position the lower portion of the perforate or foraminous side wall 23 is at the rear of the bowl and below the axis thereof. To prevent loss of material through this perforate lower portion of side wall 23 during the loading operation, a symmetrical, material retaining skirt 50 extends outside said wall portion in spaced, facing relation thereto; said skirt being closed with the bowl at the ends, as at 51, and at the lower edge of said skirt, as at 52. The space between the upper edge 53 of the skirt and the wall 23 remains open to permit discharge of material from said skirt upon rotation of the bowl.

When the bowl is loaded the sprockets 32 are rotated in the direction shown by the arrow in Fig. 4, which causes the door assembly to close, by reason of the fact that elbow link 33 draws the door 28 to closed position, while the adjacent edges of side wings 31 engage the cam faces 36 of bellcrank legs 27 to push the bellcrank 26 in a rotary direction to close the door 24.

The bowl is then raised to a carrying position, and in which position the stops 46 will miss the stops 47, due to the fact that the cross shaft 9 moves forward somewhat when raised. Thereafter at the point of unloading, and at which the implement may be stationary or moving, the sprockets are driven to cause rotation of the bowl in a counter-clockwise direction, such drive being through the elbow links 33 to the bowl unit. As the bowl so rotates, the material from the bowl is screened through the foraminous side wall 23 and thus discharged from the implements.

An example of a use to which the above described implement may be put is placer mining, wherein the placer material is dug by the rotary bowl unit when open, and then transported to a recovery plant in the bowl as closed. At the plant the implement is run over a receiving hopper and the bowl then rotates to screen out and discharge the smaller material and "fines" which drop into such hopper. This screening is facilitated by introduction of water into the bowl through the tubular shaft 9 which is perforate within the bowl, as at 54, and is formed at one end, as at 55, for detachable connection with a water supply hose. Large material remaining in

the bowl is discharged at a different point by opening the door assembly and then rotating the bowl clockwise while the latter is raised, such large material then falling through the door opening.

Another example of a use for the described implement is road construction wherein digging, hauling, washing, mixing, screening and distribution of gravel can be accomplished with the single implement.

In Fig. 6 the bowl is shown in the position to which it may be set for loading by a separate implement, and in which position the loading opening 22 opens generally upwardly. To obtain this position of the bowl the same is lowered and stops 47 are engaged from beneath by cooperating stops 56 on the bowl in circumferentially spaced relation from stops 46 and in the direction opposite door 28. This holds the bowl against clockwise rotation, and the sprockets 32 are then rotated in such direction to open the doors 24 and 28 for loading of the bowl from above.

While in the present scraper type embodiment the bowl assembly is mounted with its axis transversely of the direction of travel, and for vertical adjustment, it will be evident that for certain uses where the scraping function is unnecessary, said bowl assembly can be mounted—for example—on a truck or semi-trailer chassis on either a transverse or longitudinal axis, and non-adjustable vertically, in which case the bowl would be loaded solely from above.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A rotary bowl unit for an earth handling implement, comprising a driven, rotary bowl having a loading opening in one portion of the circumferential wall thereof, another portion of the circumferential wall of the bowl being foraminous, a door assembly mounted on the bowl adapted to close said opening, and a material retaining skirt extending outside said circumferential wall of the bowl in spaced facing relation to that part of the foraminous portion thereof which is lowermost when the bowl is in a predetermined loading position; there being closure means between the edges of said skirt and the bowl except at the one edge which is uppermost when the bowl is in said loading position whereby upon subsequent rotation of the bowl, material passing through said foraminous portion onto said skirt is then discharged over said one edge.

2. A rotary bowl unit for an earth handling implement, comprising a rotary bowl having a loading opening on one side thereof, a door assembly mounted on the bowl for movement between open and closed positions relative to said opening, and means to open and close said door assembly; the latter including a door movable from closed to open position about an axis extending immediately along the lower edge of said opening when the latter is in a predetermined

loading position, and an earth cutting and digging blade on the door along the edge thereof which is opposite said axis, the door opening means being operative to maintain said door in rigid open position, whereby with the forward movement of the implement the digging blade will dig material which will be forced over the door and directly into the drum through said opening.

3. A rotary bowl unit for an earth handling implement, comprising a rotary bowl having a loading opening on one side thereof, a door assembly mounted on the bowl for movement between open and closed positions relative to said opening, and means to open and close said door assembly; the latter including a door movable from closed to open position about an axis extending immediately along the lower edge of said opening when the latter is in a predetermined loading position, and an earth cutting and digging blade on the door along the edge thereof which is opposite said axis, the door opening means being operative to maintain said door in rigid open position, and said door when open being disposed substantially tangential to the bowl.

4. An earth handling implement comprising a frame supported above and for movement along the ground, a rotary bowl disposed with its axis transversely of the direction of travel, means mounting the bowl on the frame for vertical adjustment between raised and lowered positions, means to limit rotation of the bowl in one direction when said bowl is in lowered position, the bowl having a loading opening in one side thereof, a door assembly mounted on the bowl for movement to open or close said opening, a reversible power unit, and actuating means connecting the power unit with said door assembly and bowl; said actuating means being operative, when the bowl is in lowered position and the power unit is driven in a given direction, to initially cause closing of the door assembly.

5. An earth handling implement comprising a frame supported above and for movement along the ground, a rotary bowl disposed with its axis transversely of the direction of travel, means mounting the bowl on the frame for vertical adjustment between raised and lowered positions, means to limit rotation of the bowl in one direction when said bowl is in lowered position, the bowl having a loading opening in one side thereof, a door assembly mounted on the bowl for movement to open or close said opening, a reversible power unit, and actuating means connecting the power unit with said door assembly and bowl; said actuating means being operative, when the bowl is in lowered position and the power unit is driven in a given direction, to initially cause closing of the door assembly, and said means being operative upon movement of the bowl to raised position and continued drive of the power unit in the same direction, to then cause rotation of the bowl in said one direction.

6. An earth handling implement comprising a frame supported above and for movement along the ground, a rotary bowl disposed with its axis transversely of the direction of travel, an axial shaft supporting the bowl and projecting beyond the ends thereof, means supporting said shaft at said ends from the frame, the bowl having a loading opening in one side thereof, a door assembly including in circumferential relation a sliding door adapted to close one portion of the opening, and an outwardly swingable door

adapted to close another portion of the opening, said swingable door being pivotally mounted on a transverse axis adjacent the edge of the bowl opposite that portion closed by the sliding door, a bellcrank journaled on the shaft at one end of the bowl, one leg of said bellcrank being fixed to the sliding door at one end, the other leg of the bellcrank projecting generally toward the swinging door, a side wing on the adjacent end of the swinging door projecting generally radially inwardly toward said other leg of the bellcrank, the side wing being adapted to engage said other leg of the bellcrank to cause swinging of the latter in a direction to close the sliding door upon closing of the swinging door, a flexible link connected between the wing and said other leg of the bellcrank to pull the latter in a direction to open the sliding door upon opening of the swinging door, a sprocket on the shaft at said one end of the bowl, means to drive said sprocket in either direction selectively, and means between the sprocket and said wing to open and close the swinging door upon rotation of the sprocket in corresponding directions.

25 7. An earth handling implement comprising a frame supported above and for movement along the ground, a rotary bowl disposed with its axis transversely of the direction of travel, an axial shaft supporting the bowl and projecting beyond the ends thereof, means supporting said shaft at said ends from the frame, the bowl having a loading opening in one side thereof, a door assembly including in circumferential relation a sliding door adapted to close one portion of the opening and an outwardly swingable door adapted to close another portion of the opening, said swingable door being pivotally mounted on a transverse axis adjacent the edge of the bowl opposite that portion closed by the sliding door, a bellcrank journaled on the shaft at one end of the bowl, one leg of said bellcrank being fixed to the sliding door at one end, the other leg of the bellcrank projecting generally toward the swinging door, a side wing on the adjacent end of the swinging door projecting generally radially inwardly toward said other leg of the bellcrank, the side wing being adapted to engage said other leg of the bellcrank to cause swinging of the latter in a direction to close the sliding door upon closing of the swinging door, a flexible link connected between the wing and said other leg of the bellcrank to pull the latter in a direction to open the sliding door upon opening of the swinging door, a sprocket on the shaft at said one end of the bowl, means to drive said sprocket in either direction selectively, and an elbow link pivotally connected between an eccentric point on the sprocket and a point on the side wing so that upon rotation of the sprocket in one direction to open the swinging door, and upon reverse rotation of the sprocket to close the swing door; said elbow link extending away from the shaft, and when the door assembly is closed being disposed with the elbow adjacent thereto and with said pivot points beyond dead-center relative to the shaft axis.

75 8. An implement as in claim 6 in which the shaft is vertically adjustable to move the bowl between raised and lowered positions, means to limit rotation of the bowl in one direction when the bowl is lowered, the loading opening then being at the front of the bowl; said swinging door when open projecting forwardly from the lowermost side of the loading opening, and an

earth cutting and digging blade on the side of said door which is foremost when the door is open.

9. An implement as in claim 6 including a driven cross shaft on the frame in spaced relation to the bowl lengthwise of the implement, a sprocket on said driven cross shaft, an endless chain extending between the sprocket on the driven cross shaft and the sprocket in the bowl supporting shaft; the supporting means for said bowl supporting shaft being arranged to adjust said shaft up or down in an arcuate path concentric to said driven cross shaft.

10. An earth handling implement comprising a wheel supported frame, a rotary bowl mounted on the frame with the bowl axis extending transversely, a loading opening on one side of the bowl, another side of the bowl being foraminous, a closure means for said opening including a closure means pivoted on the bowl for swinging movement lengthwise of the implement, an earth cutting and digging blade on that edge of such pivoted door which is outermost when the door is open, means operative to open said door with the loading opening facing forwardly and with said blade projecting forwardly for ground engagement, or to open said door with the loading opening facing upwardly for loading of said pivoted bowl by a separate implement, means to prevent rotation of the bowl by the thrust of said blade when said pivoted door is open and the blade is in ground engagement, and means to rotate said bowl when the door is closed.

11. A traveling material handling implement including a supporting frame, a drum rotatably mounted in the frame, means to raise and lower the drum relative to the frame, means to hold the drum against clockwise rotation when in lowered position, the drum having a load receiving opening, a closure means for said opening including a pivoted door normally closing at least a portion of said opening, and means for swinging said door on its pivot to ground engaging position when the drum is lowered and held against clockwise rotation, whereby with forward movement of the implement material may then be scraped and delivered through the opening into the bowl.

12. A device as in claim 11 in which the door opening means is also operable to close the door and thereafter rotate the drum counterclockwise.

13. A device as in claim 11 in which the door opening means is also operable to close the door and thereafter rotate the drum counter-clockwise, at least a portion of the wall of said drum being foraminous whereby to screen material from the drum therethrough during such counter-clockwise rotation of the drum.

14. In a material handling implement, a frame, a drum rotatably mounted in the frame and provided with a load receiving opening, closure means for said opening including a pivoted door normally closing at least a portion of said opening, a gear rotatably mounted substantially co-axially of the drum, a bell crank connecting the gear and said pivoted door so that when the gear is rotated in one direction the door will be swung open and when the gear is rotated in the opposite direction the door will be closed, and co-acting stops on the gear and drum respectively adapted to engage and cause rotation of the drum upon rotation of the gear in a door opening direction and after the door is open, and means to drive the gear.

15. A travelling material handling implement

including a frame supported for movement along the ground, a power unit mounted on the frame, a rotatable drum supported by the frame, said drum having an opening through which material may be loaded into the drum, a closure means for the opening including a door one edge of which is pivoted directly to one edge of the opening, means to swing said door from a closed position over a portion of said opening to a position extending outwardly from said one edge of the opening, such means comprising a rotatable element separate from the door, means to drive the element from the power unit and a bell crank connection between the element and door.

16. A travelling material handling implement including a frame supported for movement along the ground, a power unit mounted on the frame, a rotatable drum supported by the frame, said drum having an opening through which material may be loaded into the drum, a closure means for said opening including a door one edge of which is pivoted to one edge of the opening, a rotatable gear mounted in driving relation with said power unit, and a bell crank connection between the gear and door whereby through operation of the gear the door may be swung on its pivot from closed position over a portion of the opening to an outwardly projecting position clear of the opening, and vice versa.

17. A combination as in claim 15 in which the outer edge of the door forms a scraping edge operable when the door is in said outwardly extending position to engage the ground and dig and scrape earth and move it over the door and directly into the drum with the forward movement of the implement.

18. A material handling implement including a drum to receive a load of material, such drum having a load receiving opening, a door assembly normally closing said opening, such assembly including a sliding door and a pivoted door, and means to simultaneously swing the pivoted door and slide the sliding door, said latter means including a pivoted bell crank having one leg connected with the sliding door, and a tension member connected between the pivoted door and the other leg of the bell crank whereby when the pivoted door swings open it will pull the sliding door open, and means to turn the pivoted door on its axis.

19. A material handling implement including a drum to receive a load of material, such drum having a load receiving opening, a door assembly normally closing said opening, such assembly including a sliding door and a pivoted door, and means to simultaneously swing the pivoted door and slide the sliding door, latter means including a pivoted bell crank having one leg connected with the sliding door, and a tension member connected between the pivoted door and the other leg of the bell crank whereby when the pivoted door swings open it will pull the sliding door open, means to turn the pivoted door on its axis, and means on the pivoted door to engage such other leg of the bell crank as the pivoted door swings to closed position and thereby slide the sliding door to closed position.

20. A travelling material handling element including a frame supported for movement along the ground, a rotatable drum supported by the frame, said drum having an opening through which material may be loaded into the drum, a door assembly for said opening, such assembly comprising a first arcuate shaped door arranged

75

to slide circumferentially over a portion of said opening to respectively close or open the same, a second door, said second door being substantially flat and hinged at one edge directly along one edge of the drum opening and operable to close the balance of the opening or to be extended outwardly from said one edge of the drum, and means to simultaneously swing the second door and slide the first door.

21. A travelling material handling implement including a frame supported for movement along the ground, said frame comprising spaced side walls provided with aligned substantially vertically disposed slots, a drum having an axially disposed shaft mounted for guided movement through said slots, means to raise and lower said shaft in said slots whereby to raise or lower the drum, means for scraping and loading material into the drum when the latter is in lowered position and the implement moves forward, and means to rotate the drum when it is in raised position, the walls of the drum being at least in part foraminous whereby upon rotation of the drum material will be screened therethrough.

22. A travelling material handling implement including a frame supported for movement along the ground, said frame comprising spaced side walls provided with aligned substantially vertically disposed slots, a drum having an axially disposed shaft mounted for guided movement through said slots, means to raise and lower said shaft in said slots whereby to raise or lower the drum, means for scraping and loading material into the drum when the latter is in lowered position and the implement moves forward, and means to rotate the drum when it is in raised position, said scraping and loading means including a door controlled opening in the drum, the door being normally open when the drum is in lowered position and normally closed when the drum is in said raised position, and means whereby when the drum is in said latter position and rotated clockwise the door will be opened and the contents of the drum discharged therefrom.

23. A travelling material handling implement including a frame supported for movement along the ground, said frame comprising spaced side walls provided with aligned substantially vertically disposed slots, a drum having an axially disposed shaft mounted for guided movement through said slots, means to raise and lower said shaft in said slots whereby to raise or lower the drum, means for scraping and loading material into the drum when the latter is in lowered position and the implement moves forward, and means to rotate the drum when it is in raised position, said scraping and loading means including an opening provided in the drum, a closure means for said opening including a door hinged along one edge thereof directly to one edge of the opening, means to close the door at least a portion of over the opening when the drum is in raised position or to extend the door outwardly from said opening when the drum is in lowered position, means to

hold the drum against clockwise rotation when in said latter position, the door then being operable to scrape material which will be forced into the drum through said opening with the forward movement of the implement.

24. In a material handling implement, a frame, a drum mounted for rotation in the frame, means to move the drum vertically relative to the frame, means to move the drum rearwardly relative to the frame when said drum is moved downwardly, a yieldable stop on the frame, a stop on the drum positioned to engage and pass the yieldable stop as the drum moves downwardly and rearwardly, the stops then engaging each other to prevent rotation of the drum in one direction, and means whereby material may be loaded into the drum when it is in lowered position.

25. In a material handling implement, a frame comprising spaced side walls provided with aligned substantially vertically disposed slots, a shaft mounted for movement through said slots, a drum mounted on the shaft, a bell crank journaled on the frame, one arm of the bell crank being slidably connected with the shaft, and means connected with the other end of the bell crank for moving the bell crank on its axis whereby to selectively raise or lower the drum, means whereby material may be loaded into the drum, a gear mounted for rotation on the shaft, a second shaft mounted in the frame, the slots being arcuate in shape and disposed concentric with the axis of said second shaft, a gear fixed on said second shaft, the two gears being connected in driving relation with each other, means to drive the second shaft, and means to selectively place the gear on the first shaft in driving relation with the drum to rotate said drum either clockwise or counter-clockwise.

LAURENCE L. RECKLER.
